UNITED STATES PATENT OFFICE.

ROY CROSS, OF KANSAS CITY, MISSOURI, ASSIGNOR TO GASOLINE PRODUCTS COMPANY, OF NEW YORK, N. Y., A CORPORATION OF NEW YORK.

COKING STILL.

Application filed April 12, 1924. Serial No. 706,020.

This invention relates to improvements in a coking still, and refers more particularly to an apparatus for treating heavy hydrocarbons in order to distill off the volatile material and reduce the bottoms to petroleum coke.

Among the salient objects of the invention are, to provide a still which eliminates the accumulation and collection of the petroleum carbon or coky material on the bottom of the still where, in the normal type of construction, it serves to insulate the oil from the heat of the still and reduce the still's efficiency; to provide a still in which the carbon or coky material is continuously scraped from the inside surface as the still rotates and supplies a means for collecting this carbonaceous material in a removable container or basket wherein the carbonaceous substance is accumulated in a loose, dry condition; to provide a still which is more efficiently heated due to the heat conducting vanes upon its outer periphery.

In the drawings,

Fig. 1 is a diagrammatic side elevational view of the still, with parts in section.

Fig. 2 is a cross sectional view taken along the line 2—2 in Fig. 1, looking in the direction of the arrow.

Referring to the drawings, at 1 is shown a rotatable still supported by standards 2 and bearing upon a shaft 3. "4" is an oven or furnace arrangement surrounding the rotatable still and preferably heated by means of gas burner diagrammatically shown at 5. "6" is a carbon basket suspended from the shaft 3 by hangers 3^a which rotatably bear upon the shaft. The basket is removable from the still to a position shown in dotted lines at 6^a by sliding the hangers along the shaft. To remove the vaporized material from the still, an internally positioned open-ended pipe 7 is connected to the hollow portion of the shaft shown at 8 which terminates in an elbow connection to the vapor line 9. This latter line has communication with the condenser coil 10 in the condenser box 11, the discharge from the coil terminating in the receiving tank 12 which is equipped with a liquid level gauge 13 and a liquid drawoff valve 14.

The still is rotated by means of the driving gears 15, mounted on shafts 16, and driven from any convenient source not

shown. Both or either of the gears may be driven while the other may serve merely as an additional support to the still. These gears 15 mesh with girth gears 17 circumferentially positioned on the periphery of the still. The shaft 3 is stationary, and the bearing 18 surrounding the vapor line is preferably water-cooled, although not shown so in the drawing, as this detail is not a part of the present invention.

The opposite end of the still is fitted with a removable plate 19 which may be slid along the shaft 3 to the dotted line position 19^a in order that the carbon basket or container 6 may be removed from the still in order to clean the carbon therefrom. On the outer shell of the still is a plurality of ridges or heat absorbing vanes designated as 20 which, upon rotation of the still, serve to more efficiently and uniformly heat its contents due to the increased surface exposed to the heating gases. This basket or container 6 extends substantially the entire length of the still in order to catch the carbon which is scraped from the inside shell by a scraper 21 pivoted at 22 on one edge of the carbon basket. When the carbon basket has been pushed into the still, the scraper is swung over so that its blade contacts the inner surface of the still as shown in Fig. 2.

The oil charged may be introduced through the open end of the still or through a separate charging pipe not shown. When the endplate has been bolted in position after the still has been charged, fire is started in the furnace or oven and the still rotated while the oil is being heated. It is important that the level of the oil charged is below the bottom of the carbon basket in order that the carbonaceous material collected in the basket will not be fouled with the sludgy oil but may be removed in a comparatively loose, dry state.

As the still is heated, the vapors evolved will pass off through the pipe 7, through the hollow bearing and out into the vapor line 9, being condensed in the coil 10 and collected as distillate in the receiving tank 12. The heating is continued until substantially all of the volatile material has been driven off, and the coky material collected as dry carbon in the carbon basket or container 6. The collection of the carbon is

effected by scraping the deposited material from the inside of the still into the basket by means of the scraper 21.

When the petroleum products have been 5 reduced to a coky mass, substantially all of which is scraped into the carbon basket, the fire is extinguished and the still permitted to cool or is steamed out to facilitate cooling. The endplate 9 is moved back to a position 10 shown at 19^a and a carbon basket withdrawn from the still to a dotted line position shown at 6^a. When placed thus, the carbon and coky material can easily be removed while the still is yet too hot for workmen to enter. 15 The advantages of this type of construction are obvious, as it permits more efficient heating, eliminating the collection and accumulation of carbon on the bottom of the still which tends to insulate it against efficient 20 heating. It also supplies a means for removing the petroleum coke from the interior of a coking still without necessitating manual labor in digging and scraping the coke from the interior shell, which is not only expensive and slow, but is disagreeable and often-times difficult when the oil has been reduced 25 to a relatively dry product.

The construction permits the accumulation 30 and collection of petroleum coke in a relatively loose, flaky condition in a separate container which is easily removed from the still while the still would normally be too hot for carbon to be dug out by manual labor. This reduces the time in which the still 35 is shut down for cleaning, and greatly increases the saving, both in heat loss and labor necessary for the removal of this petroleum coke.

In addition to this, it increases the life 40 of the still, as there is less tendency for the shell to become overheated due to the production of hot spots where carbon has collected. As described, the heat absorbing vanes serve to more evenly distribute and uniformly 45 transmit the heat to the oil, at the same time supplying heat more rapidly due to the increased surface exposed.

Certain obvious details of construction 50 have been eliminated in order to simplify the drawings. It is understood, however, that the invention broadly covers the utilization of a carbon container in a rotating still whereby the petroleum carbon, or coky material deposited during the coking operation, 55 is collected therein by continuously scraping the same from the inner surface of the still as it rotates.

I claim as my invention:

1. In an apparatus for coking petroleum 60 hydrocarbons, the combination with a still adapted to be heated to sufficient temperature to distill off the volatile material, means for

scraping the deposited carbonaceous substance from the still walls, and a container supported in the still for maintaining said 65 removed carbonaceous material out of contact with the shell of said still, said scraping means mounted upon the container.

2. In an apparatus for coking petroleum hydrocarbons, the combination with a still 70 adapted to be heated to sufficient temperature to distill off the volatile material, means for scraping the deposited carbonaceous substance from the interior of the still, a removable container positioned therein for collecting said substance, said scraper hinged upon the container and adapted to be placed in an operable or inoperable position.

3. In an apparatus for coking petroleum hydrocarbons, the combination with a revolving 80 still adapted to be sufficiently heated to distill off the volatile material, of a container suspended in said still, and a scraping means for scraping the deposited carbon from the inside surface of the still into the 85 container, a support carrying the container upon which the container may be moved either into or out of the still.

4. In an apparatus for coking petroleum hydrocarbons, the combination with a revolving 90 still adapted to be sufficiently heated to distill off the volatile material, of a container suspended in said still, a scraping means for scraping the deposited carbon from the inside surface of the still into the container, a 95 support upon which the container is hung adapted to facilitate its removal from the still for dumping.

5. In an apparatus for coking petroleum hydrocarbons, the combination with a rotating 100 still mounted in a furnace, of means for removing the volatilized material, means for scraping the deposited carbonaceous substance from the interior of the still, a support extending into said still, a container suspended therefrom for collecting the carbonaceous material, said container adapted 105 to be moved into or out of the still while being suspended from said support.

6. In an apparatus for coking petroleum hydrocarbons, the combination with a rotating 110 still mounted in a furnace, of means for removing the volatilized material, means for scraping the deposited carbonaceous substance from the interior of the still, a support extending into said still, a container suspended therefrom for collecting the carbonaceous material, said container adapted to be moved into or out of the still while being suspended from said support, said scraper 115 adapted to be placed in an inoperative position when the container is removed from the still.

ROY CROSS.
